IGNITION BREAKER

Vernon E. Heil, Indianapolis, Ind., and Frederick J. Heoven, Dayton, Ohio; said Heil assignor to P. R. Mallory & Co., Inc., Indianapolis, Ind., a corporation of Delaware

Application October 3, 1955, Serial No. 538,046

9 Claims. (Cl. 200—30)

This invention relates to periodic circuit breakers, particularly circuit breakers used by ignition timers for internal combustion engines.

The prime consideration in timer systems is to provide contact breakers wherein the alignment of contacts during the operation of the system is maintained substantially without variation and wherein any undesirable variation in effectively rotationally centering the contact arm during the process of opening and breaking contact is avoided.

It has been found that the fulcrum type circuit breaker possesses great advantages in providing an exact contact alignment and that such circuit breakers are able to maintain the angular position of an ideal pivoted type of breaker arm having no clearance on the pivoted bearings. The present invention, moreover, is an improvement on the fulcrum type ignition breaker assemblies heretofore known in that it lowers the costs thereof for use in several types of magneto applications.

In the present invention the fulcrum has been bent up out of the metal base and there has been inserted a thin, longitudinal strip of phenolic insulation placed between the fulcrum and the breaker arm. This thin, phenolic insulator, held at one end on the fulcrum and remaining free on the other end, serves also to insulate the breaker arm from the base at both the stock and the fulcrum point, and, in addition, also serves as a rubbing block which is adapted to ride on the cam of the ignition timer. Thus, there has been provided a new type of rubbing mechanism including a strip of insulator material connected to the break arm assembly. This results in the great advantage of cost reduction, since by its novel construction there is obviated the expense of angle moulding, sawing and drilling and also the additional cost of attaching a rubbing block to an arm.

It thus becomes apparent that the novel construction hereinafter described provides a new and improved modification of the fulcrum type assembly known to provide great advantages in rapid contact make-and-break ignition timers without any loss of alignment or increase in contact erosion.

It is therefore an object of the present invention to provide novel improved circuit breaker mechanisms for ignition timers.

It is still another object of the present invention to provide an improved circuit breaker mechanism which is easy to assemble and has an improved efficiency operation.

It is another object of the present invention to provide a light weight improved circuit breaker arm mechanism which is easy to fabricate and utilize in circuit applications needing lower weight and increased efficiency for timers operating at higher frequencies.

Still another object of the present invention is to provide an improved ignition breaker arm assembly using the fulcrum principle and which is adapted to obviate the need of a separate rubbing block component assembly therein.

2

A further object of the present invention is to provide an ignition circuit breaker arm mechanism having an improved construction which is lighter in weight, more economical to assemble and fabricate, and wherein the material and parts are of lower cost.

Another object of the present invention is to provide an ignition breaker arm means utilizing a fulcrum type principle which provides assembly procedures to attain reduced assembly costs.

10 The invention in another of its aspects relates to the novel features of the instrumentalities described herein for teaching the principal objects of the invention and to the principles embodied in these instrumentalities, whether or not these features and principles may be used in the said objects and/or in similar fields.

15 Other objects of the invention and the nature thereof will become apparent from the following description, considered in connection with the accompanying figures of the drawing and wherein like reference characters describe elements of similar function therein and where the scope of the invention is determined from the dependent claims.

Referring now to the drawing:

20 Fig. 1 is a top plan view of an embodiment of the improved fulcrum type breaker of the subject invention useful in showing the mounting of the contactor elements on the plate structure of the ignition circuit contact breaker;

25 Fig. 2 is a vertical, cross-sectional view of an embodiment of the fulcrum type ignition contact breaker adapted to illustrate the novel construction and arrangement of parts providing a breaker having exact contact alignment, as heretofore used; and

30 Fig. 3 is a pictorial exploded view of the moving arm assembly of the ignition timer including a steel spring adapted to fit within the confines thereof to overlie the same and to place it under tension.

35 Generally speaking, the fulcrum type ignition timer of 40 the present invention comprises, in combination, an assembly having means adapted to be connected to the timer of an internal combustion engine wherein said means includes an extension plate and an assembly side wall. The plate extends from the side wall at substantially right angles thereto and a plurality of slots are cut through the side wall for movably adapting the assembly to the timer. A bracket is connected to said assembly side wall and includes a terminal for an electrical connection. A steel spring, adapted to carry a rivet and a

45 contact and to cooperatively make with a fixed contact, is also connected to said bracket assembly, which further includes an insulator strip acting as a rubbing block. A movable arm is placed beneath the steel spring with the tip end thereof resting against the insulator strip. The fulcrum arm is connected to the side wall of the assembly and is placed on the opposite side of the insulator strip beneath the tip end of the movable arm. The moving arm is thus adapted to move about the fulcrum on said strip, which also is adapted to be utilized as a rubbing block.

50 It is apparent, therefore, that the components herein are adapted to perform a multiplicity of functions and to eliminate the necessity for exact alignment assemblies while providing these exact alignment features. At 55 the same time, the materials needed for other breaker arm construction of the fulcrum type are eliminated, substantially reducing the cost thereof. In addition, the weight of the breaker arm assembly is lessened, making the new and improved fulcrum type assembly construction hereinafter described adaptable for use in light weight magneto applications.

60 As shown in Figs. 1 and 2, the improved fulcrum type 65 construction of the present invention includes a base plate having a central slot 100 through which a fulcrum arm 102 extends. A side wall 104 is connected to the base plate 100 and extends generally vertically. A fixed contact 106 is secured to the side wall 104 and is connected to a steel spring 108. A movable arm 110 is secured to the steel spring 108 and is connected to a fulcrum arm 102. A bracket 112 is secured to the side wall 104 and is connected to the steel spring 108. A terminal 114 is secured to the bracket 112. A slot 116 is formed in the side wall 104 and a slot 118 is formed in the base plate 100. A slot 120 is formed in the side wall 104 and a slot 122 is formed in the base plate 100. A slot 124 is formed in the side wall 104 and a slot 126 is formed in the base plate 100. A slot 128 is formed in the side wall 104 and a slot 130 is formed in the base plate 100. A slot 132 is formed in the side wall 104 and a slot 134 is formed in the base plate 100. A slot 136 is formed in the side wall 104 and a slot 138 is formed in the base plate 100. A slot 140 is formed in the side wall 104 and a slot 142 is formed in the base plate 100. A slot 144 is formed in the side wall 104 and a slot 146 is formed in the base plate 100. A slot 148 is formed in the side wall 104 and a slot 150 is formed in the base plate 100. A slot 152 is formed in the side wall 104 and a slot 154 is formed in the base plate 100. A slot 156 is formed in the side wall 104 and a slot 158 is formed in the base plate 100. A slot 160 is formed in the side wall 104 and a slot 162 is formed in the base plate 100. A slot 164 is formed in the side wall 104 and a slot 166 is formed in the base plate 100. A slot 168 is formed in the side wall 104 and a slot 170 is formed in the base plate 100. A slot 172 is formed in the side wall 104 and a slot 174 is formed in the base plate 100. A slot 176 is formed in the side wall 104 and a slot 178 is formed in the base plate 100. A slot 180 is formed in the side wall 104 and a slot 182 is formed in the base plate 100. A slot 184 is formed in the side wall 104 and a slot 186 is formed in the base plate 100. A slot 188 is formed in the side wall 104 and a slot 190 is formed in the base plate 100. A slot 192 is formed in the side wall 104 and a slot 194 is formed in the base plate 100. A slot 196 is formed in the side wall 104 and a slot 198 is formed in the base plate 100. A slot 200 is formed in the side wall 104 and a slot 202 is formed in the base plate 100. A slot 204 is formed in the side wall 104 and a slot 206 is formed in the base plate 100. A slot 208 is formed in the side wall 104 and a slot 210 is formed in the base plate 100. A slot 212 is formed in the side wall 104 and a slot 214 is formed in the base plate 100. A slot 216 is formed in the side wall 104 and a slot 218 is formed in the base plate 100. A slot 220 is formed in the side wall 104 and a slot 222 is formed in the base plate 100. A slot 224 is formed in the side wall 104 and a slot 226 is formed in the base plate 100. A slot 228 is formed in the side wall 104 and a slot 230 is formed in the base plate 100. A slot 232 is formed in the side wall 104 and a slot 234 is formed in the base plate 100. A slot 236 is formed in the side wall 104 and a slot 238 is formed in the base plate 100. A slot 240 is formed in the side wall 104 and a slot 242 is formed in the base plate 100. A slot 244 is formed in the side wall 104 and a slot 246 is formed in the base plate 100. A slot 248 is formed in the side wall 104 and a slot 250 is formed in the base plate 100. A slot 252 is formed in the side wall 104 and a slot 254 is formed in the base plate 100. A slot 256 is formed in the side wall 104 and a slot 258 is formed in the base plate 100. A slot 260 is formed in the side wall 104 and a slot 262 is formed in the base plate 100. A slot 264 is formed in the side wall 104 and a slot 266 is formed in the base plate 100. A slot 268 is formed in the side wall 104 and a slot 270 is formed in the base plate 100. A slot 272 is formed in the side wall 104 and a slot 274 is formed in the base plate 100. A slot 276 is formed in the side wall 104 and a slot 278 is formed in the base plate 100. A slot 280 is formed in the side wall 104 and a slot 282 is formed in the base plate 100. A slot 284 is formed in the side wall 104 and a slot 286 is formed in the base plate 100. A slot 288 is formed in the side wall 104 and a slot 290 is formed in the base plate 100. A slot 292 is formed in the side wall 104 and a slot 294 is formed in the base plate 100. A slot 296 is formed in the side wall 104 and a slot 298 is formed in the base plate 100. A slot 300 is formed in the side wall 104 and a slot 302 is formed in the base plate 100. A slot 304 is formed in the side wall 104 and a slot 306 is formed in the base plate 100. A slot 308 is formed in the side wall 104 and a slot 310 is formed in the base plate 100. A slot 312 is formed in the side wall 104 and a slot 314 is formed in the base plate 100. A slot 316 is formed in the side wall 104 and a slot 318 is formed in the base plate 100. A slot 320 is formed in the side wall 104 and a slot 322 is formed in the base plate 100. A slot 324 is formed in the side wall 104 and a slot 326 is formed in the base plate 100. A slot 328 is formed in the side wall 104 and a slot 330 is formed in the base plate 100. A slot 332 is formed in the side wall 104 and a slot 334 is formed in the base plate 100. A slot 336 is formed in the side wall 104 and a slot 338 is formed in the base plate 100. A slot 340 is formed in the side wall 104 and a slot 342 is formed in the base plate 100. A slot 344 is formed in the side wall 104 and a slot 346 is formed in the base plate 100. A slot 348 is formed in the side wall 104 and a slot 350 is formed in the base plate 100. A slot 352 is formed in the side wall 104 and a slot 354 is formed in the base plate 100. A slot 356 is formed in the side wall 104 and a slot 358 is formed in the base plate 100. A slot 360 is formed in the side wall 104 and a slot 362 is formed in the base plate 100. A slot 364 is formed in the side wall 104 and a slot 366 is formed in the base plate 100. A slot 368 is formed in the side wall 104 and a slot 370 is formed in the base plate 100. A slot 372 is formed in the side wall 104 and a slot 374 is formed in the base plate 100. A slot 376 is formed in the side wall 104 and a slot 378 is formed in the base plate 100. A slot 380 is formed in the side wall 104 and a slot 382 is formed in the base plate 100. A slot 384 is formed in the side wall 104 and a slot 386 is formed in the base plate 100. A slot 388 is formed in the side wall 104 and a slot 390 is formed in the base plate 100. A slot 392 is formed in the side wall 104 and a slot 394 is formed in the base plate 100. A slot 396 is formed in the side wall 104 and a slot 398 is formed in the base plate 100. A slot 400 is formed in the side wall 104 and a slot 402 is formed in the base plate 100. A slot 404 is formed in the side wall 104 and a slot 406 is formed in the base plate 100. A slot 408 is formed in the side wall 104 and a slot 410 is formed in the base plate 100. A slot 412 is formed in the side wall 104 and a slot 414 is formed in the base plate 100. A slot 416 is formed in the side wall 104 and a slot 418 is formed in the base plate 100. A slot 420 is formed in the side wall 104 and a slot 422 is formed in the base plate 100. A slot 424 is formed in the side wall 104 and a slot 426 is formed in the base plate 100. A slot 428 is formed in the side wall 104 and a slot 430 is formed in the base plate 100. A slot 432 is formed in the side wall 104 and a slot 434 is formed in the base plate 100. A slot 436 is formed in the side wall 104 and a slot 438 is formed in the base plate 100. A slot 440 is formed in the side wall 104 and a slot 442 is formed in the base plate 100. A slot 444 is formed in the side wall 104 and a slot 446 is formed in the base plate 100. A slot 448 is formed in the side wall 104 and a slot 450 is formed in the base plate 100. A slot 452 is formed in the side wall 104 and a slot 454 is formed in the base plate 100. A slot 456 is formed in the side wall 104 and a slot 458 is formed in the base plate 100. A slot 460 is formed in the side wall 104 and a slot 462 is formed in the base plate 100. A slot 464 is formed in the side wall 104 and a slot 466 is formed in the base plate 100. A slot 468 is formed in the side wall 104 and a slot 470 is formed in the base plate 100. A slot 472 is formed in the side wall 104 and a slot 474 is formed in the base plate 100. A slot 476 is formed in the side wall 104 and a slot 478 is formed in the base plate 100. A slot 480 is formed in the side wall 104 and a slot 482 is formed in the base plate 100. A slot 484 is formed in the side wall 104 and a slot 486 is formed in the base plate 100. A slot 488 is formed in the side wall 104 and a slot 490 is formed in the base plate 100. A slot 492 is formed in the side wall 104 and a slot 494 is formed in the base plate 100. A slot 496 is formed in the side wall 104 and a slot 498 is formed in the base plate 100. A slot 500 is formed in the side wall 104 and a slot 502 is formed in the base plate 100. A slot 504 is formed in the side wall 104 and a slot 506 is formed in the base plate 100. A slot 508 is formed in the side wall 104 and a slot 510 is formed in the base plate 100. A slot 512 is formed in the side wall 104 and a slot 514 is formed in the base plate 100. A slot 516 is formed in the side wall 104 and a slot 518 is formed in the base plate 100. A slot 520 is formed in the side wall 104 and a slot 522 is formed in the base plate 100. A slot 524 is formed in the side wall 104 and a slot 526 is formed in the base plate 100. A slot 528 is formed in the side wall 104 and a slot 530 is formed in the base plate 100. A slot 532 is formed in the side wall 104 and a slot 534 is formed in the base plate 100. A slot 536 is formed in the side wall 104 and a slot 538 is formed in the base plate 100. A slot 540 is formed in the side wall 104 and a slot 542 is formed in the base plate 100. A slot 544 is formed in the side wall 104 and a slot 546 is formed in the base plate 100. A slot 548 is formed in the side wall 104 and a slot 550 is formed in the base plate 100. A slot 552 is formed in the side wall 104 and a slot 554 is formed in the base plate 100. A slot 556 is formed in the side wall 104 and a slot 558 is formed in the base plate 100. A slot 560 is formed in the side wall 104 and a slot 562 is formed in the base plate 100. A slot 564 is formed in the side wall 104 and a slot 566 is formed in the base plate 100. A slot 568 is formed in the side wall 104 and a slot 570 is formed in the base plate 100. A slot 572 is formed in the side wall 104 and a slot 574 is formed in the base plate 100. A slot 576 is formed in the side wall 104 and a slot 578 is formed in the base plate 100. A slot 580 is formed in the side wall 104 and a slot 582 is formed in the base plate 100. A slot 584 is formed in the side wall 104 and a slot 586 is formed in the base plate 100. A slot 588 is formed in the side wall 104 and a slot 590 is formed in the base plate 100. A slot 592 is formed in the side wall 104 and a slot 594 is formed in the base plate 100. A slot 596 is formed in the side wall 104 and a slot 598 is formed in the base plate 100. A slot 600 is formed in the side wall 104 and a slot 602 is formed in the base plate 100. A slot 604 is formed in the side wall 104 and a slot 606 is formed in the base plate 100. A slot 608 is formed in the side wall 104 and a slot 610 is formed in the base plate 100. A slot 612 is formed in the side wall 104 and a slot 614 is formed in the base plate 100. A slot 616 is formed in the side wall 104 and a slot 618 is formed in the base plate 100. A slot 620 is formed in the side wall 104 and a slot 622 is formed in the base plate 100. A slot 624 is formed in the side wall 104 and a slot 626 is formed in the base plate 100. A slot 628 is formed in the side wall 104 and a slot 630 is formed in the base plate 100. A slot 632 is formed in the side wall 104 and a slot 634 is formed in the base plate 100. A slot 636 is formed in the side wall 104 and a slot 638 is formed in the base plate 100. A slot 640 is formed in the side wall 104 and a slot 642 is formed in the base plate 100. A slot 644 is formed in the side wall 104 and a slot 646 is formed in the base plate 100. A slot 648 is formed in the side wall 104 and a slot 650 is formed in the base plate 100. A slot 652 is formed in the side wall 104 and a slot 654 is formed in the base plate 100. A slot 656 is formed in the side wall 104 and a slot 658 is formed in the base plate 100. A slot 660 is formed in the side wall 104 and a slot 662 is formed in the base plate 100. A slot 664 is formed in the side wall 104 and a slot 666 is formed in the base plate 100. A slot 668 is formed in the side wall 104 and a slot 670 is formed in the base plate 100. A slot 672 is formed in the side wall 104 and a slot 674 is formed in the base plate 100. A slot 676 is formed in the side wall 104 and a slot 678 is formed in the base plate 100. A slot 680 is formed in the side wall 104 and a slot 682 is formed in the base plate 100. A slot 684 is formed in the side wall 104 and a slot 686 is formed in the base plate 100. A slot 688 is formed in the side wall 104 and a slot 690 is formed in the base plate 100. A slot 692 is formed in the side wall 104 and a slot 694 is formed in the base plate 100. A slot 696 is formed in the side wall 104 and a slot 698 is formed in the base plate 100. A slot 700 is formed in the side wall 104 and a slot 702 is formed in the base plate 100. A slot 704 is formed in the side wall 104 and a slot 706 is formed in the base plate 100. A slot 708 is formed in the side wall 104 and a slot 710 is formed in the base plate 100. A slot 712 is formed in the side wall 104 and a slot 714 is formed in the base plate 100. A slot 716 is formed in the side wall 104 and a slot 718 is formed in the base plate 100. A slot 720 is formed in the side wall 104 and a slot 722 is formed in the base plate 100. A slot 724 is formed in the side wall 104 and a slot 726 is formed in the base plate 100. A slot 728 is formed in the side wall 104 and a slot 730 is formed in the base plate 100. A slot 732 is formed in the side wall 104 and a slot 734 is formed in the base plate 100. A slot 736 is formed in the side wall 104 and a slot 738 is formed in the base plate 100. A slot 740 is formed in the side wall 104 and a slot 742 is formed in the base plate 100. A slot 744 is formed in the side wall 104 and a slot 746 is formed in the base plate 100. A slot 748 is formed in the side wall 104 and a slot 750 is formed in the base plate 100. A slot 752 is formed in the side wall 104 and a slot 754 is formed in the base plate 100. A slot 756 is formed in the side wall 104 and a slot 758 is formed in the base plate 100. A slot 760 is formed in the side wall 104 and a slot 762 is formed in the base plate 100. A slot 764 is formed in the side wall 104 and a slot 766 is formed in the base plate 100. A slot 768 is formed in the side wall 104 and a slot 770 is formed in the base plate 100. A slot 772 is formed in the side wall 104 and a slot 774 is formed in the base plate 100. A slot 776 is formed in the side wall 104 and a slot 778 is formed in the base plate 100. A slot 780 is formed in the side wall 104 and a slot 782 is formed in the base plate 100. A slot 784 is formed in the side wall 104 and a slot 786 is formed in the base plate 100. A slot 788 is formed in the side wall 104 and a slot 790 is formed in the base plate 100. A slot 792 is formed in the side wall 104 and a slot 794 is formed in the base plate 100. A slot 796 is formed in the side wall 104 and a slot 798 is formed in the base plate 100. A slot 800 is formed in the side wall 104 and a slot 802 is formed in the base plate 100. A slot 804 is formed in the side wall 104 and a slot 806 is formed in the base plate 100. A slot 808 is formed in the side wall 104 and a slot 810 is formed in the base plate 100. A slot 812 is formed in the side wall 104 and a slot 814 is formed in the base plate 100. A slot 816 is formed in the side wall 104 and a slot 818 is formed in the base plate 100. A slot 820 is formed in the side wall 104 and a slot 822 is formed in the base plate 100. A slot 824 is formed in the side wall 104 and a slot 826 is formed in the base plate 100. A slot 828 is formed in the side wall 104 and a slot 830 is formed in the base plate 100. A slot 832 is formed in the side wall 104 and a slot 834 is formed in the base plate 100. A slot 836 is formed in the side wall 104 and a slot 838 is formed in the base plate 100. A slot 840 is formed in the side wall 104 and a slot 842 is formed in the base plate 100. A slot 844 is formed in the side wall 104 and a slot 846 is formed in the base plate 100. A slot 848 is formed in the side wall 104 and a slot 850 is formed in the base plate 100. A slot 852 is formed in the side wall 104 and a slot 854 is formed in the base plate 100. A slot 856 is formed in the side wall 104 and a slot 858 is formed in the base plate 100. A slot 860 is formed in the side wall 104 and a slot 862 is formed in the base plate 100. A slot 864 is formed in the side wall 104 and a slot 866 is formed in the base plate 100. A slot 868 is formed in the side wall 104 and a slot 870 is formed in the base plate 100. A slot 872 is formed in the side wall 104 and a slot 874 is formed in the base plate 100. A slot 876 is formed in the side wall 104 and a slot 878 is formed in the base plate 100. A slot 880 is formed in the side wall 104 and a slot 882 is formed in the base plate 100. A slot 884 is formed in the side wall 104 and a slot 886 is formed in the base plate 100. A slot 888 is formed in the side wall 104 and a slot 890 is formed in the base plate 100. A slot 892 is formed in the side wall 104 and a slot 894 is formed in the base plate 100. A slot 896 is formed in the side wall 104 and a slot 898 is formed in the base plate 100. A slot 900 is formed in the side wall 104 and a slot 902 is formed in the base plate 100. A slot 904 is formed in the side wall 104 and a slot 906 is formed in the base plate 100. A slot 908 is formed in the side wall 104 and a slot 910 is formed in the base plate 100. A slot 912 is formed in the side wall 104 and a slot 914 is formed in the base plate 100. A slot 916 is formed in the side wall 104 and a slot 918 is formed in the base plate 100. A slot 920 is formed in the side wall 104 and a slot 922 is formed in the base plate 100. A slot 924 is formed in the side wall 104 and a slot 926 is formed in the base plate 100. A slot 928 is formed in the side wall 104 and a slot 930 is formed in the base plate 100. A slot 932 is formed in the side wall 104 and a slot 934 is formed in the base plate 100. A slot 936 is formed in the side wall 104 and a slot 938 is formed in the base plate 100. A slot 940 is formed in the side wall 104 and a slot 942 is formed in the base plate 100. A slot 944 is formed in the side wall 104 and a slot 946 is formed in the base plate 100. A slot 948 is formed in the side wall 104 and a slot 950 is formed in the base plate 100. A slot 952 is formed in the side wall 104 and a slot 954 is formed in the base plate 100. A slot 956 is formed in the side wall 104 and a slot 958 is formed in the base plate 100. A slot 960 is formed in the side wall 104 and a slot 962 is formed in the base plate 100. A slot 964 is formed in the side wall 104 and a slot 966 is formed in the base plate 100. A slot 968 is formed in the side wall 104 and a slot 970 is formed in the base plate 100. A slot 972 is formed in the side wall 104 and a slot 974 is formed in the base plate 100. A slot 976 is formed in the side wall 104 and a slot 978 is formed in the base plate 100. A slot 980 is formed in the side wall 104 and a slot 982 is formed in the base plate 100. A slot 984 is formed in the side wall 104 and a slot 986 is formed in the base plate 100. A slot 988 is formed in the side wall 104 and a slot 990 is formed in the base plate 100. A slot 992 is formed in the side wall 104 and a slot 994 is formed in the base plate 100. A slot 996 is formed in the side wall 104 and a slot 998 is formed in the base plate 100. A slot 1000 is formed in the side wall 104 and a slot 1002 is formed in the base plate 100. A slot 1004 is formed in the side wall 104 and a slot 1006 is formed in the base plate 100. A slot 1008 is formed in the side wall 104 and a slot 1010 is formed in the base plate 100. A slot 1012 is formed in the side wall 104 and a slot 1014 is formed in the base plate 100. A slot 1016 is formed in the side wall 104 and a slot 1018 is formed in the base plate 100. A slot 1020 is formed in the side wall 104 and a slot 1022 is formed in the base plate 100. A slot 1024 is formed in the side wall 104 and a slot 1026 is formed in the base plate 100. A slot 1028 is formed in the side wall 104 and a slot 1030 is formed in the base plate 100. A slot 1032 is formed in the side wall 104 and a slot 1034 is formed in the base plate 100. A slot 1036 is formed in the side wall 104 and a slot 1038 is formed in the base plate 100. A slot 1040 is formed in the side wall 104 and a slot 1042 is formed in the base plate 100. A slot 1044 is formed in the side wall 104 and a slot 1046 is formed in the base plate 100. A slot 1048 is formed in the side wall 104 and a slot 1050 is formed in the base plate 100. A slot 1052 is formed in the side wall 104 and a slot 1054 is formed in the base plate 100. A slot 1056 is formed in the side wall 104 and a slot 1058 is formed in the base plate 100. A slot 1060 is formed in the side wall 104 and a slot 1062 is formed in the base plate 100. A slot 1064 is formed in the side wall 104 and a slot 1066 is formed in the base plate 100. A slot 1068 is formed in the side wall 104 and a slot 1070 is formed in the base plate 100. A slot 1072 is formed in the side wall 104 and a slot 1074 is formed in the base plate 100. A slot 1076 is formed in the side wall 104 and a slot 1078 is formed in the base plate 100. A slot 1080 is formed in the side wall 104 and a slot 1082 is formed in the base plate 100. A slot 1084 is formed in the side wall 104 and a slot 1086 is formed in the base plate 100. A slot 1088 is formed in the side wall 104 and a slot 1090 is formed in the base plate 100. A slot 1092 is formed in the side wall 104 and a slot 1094 is formed in the base plate 100. A slot 1096 is formed in the side wall 104 and a slot 1098 is formed in the base plate 100. A slot 1100 is formed in the side wall 104 and a slot 1102 is formed in the base plate 100. A slot 1104 is formed in the side wall 104 and a slot 1106 is formed in the base plate 100. A slot 1108 is formed in the side wall 104 and a slot 1110 is formed in the base plate 100. A slot 1112 is formed in the side wall 104 and a slot 1114 is formed in the base plate 100. A slot 1116 is formed in the side wall 104 and a slot 1118 is formed in the base plate 100. A slot 1120 is formed in the side wall 104 and a slot 1122 is formed in the base plate 100. A slot 1124 is formed in the side wall 104 and a slot 1126 is formed in the base plate 100. A slot 1128 is formed in the side wall 104 and a slot 1130 is formed in the base plate 100. A slot 1132 is formed in the side wall 104 and a slot 1134 is formed in the base plate 100. A slot 1136 is formed in the side wall 104 and a slot 1138 is formed in the base plate 100. A slot 1140 is formed in the side wall 104 and a slot 1142 is formed in the base plate 100. A slot 1144 is formed in the side wall 104 and a slot 1146 is formed in the base plate 100. A slot 1148 is formed in the side wall 104 and a slot 1150 is formed in the base plate 100. A slot 1152 is formed in the side wall 104 and a slot 1154 is formed in the base plate

breaker comprises an assembly 10 including a side wall 11 having a lateral extension 12, a fulcrum bar 13 and a tongue extension 14. The side wall structure 11 has a configuration such as to define a middle curved section 29 interconnecting two end sections 31 and 32, each of which has an aperture cut therethrough for mounting purposes. The base has an upper surface 33 and a lower surface 34. At end 32 on lower surface 34 extending substantially 90° thereto is a flat tongue extension 14, suitably fabricated of metal, for carrying contact 23 thereon. Opposite thereto and extending from the upper surface 33, bent substantially at right angles thereto, is a flat, lateral extension 12. On one side 15 of lateral extension 12 an insulator pad 16, fabricated of a material such as phenol, is placed. On the other side of extension 12 is formed a phenolic insulator strip 18 which extends longitudinally toward extension 14. Over the insulator strip and above extension 12 is formed a terminal post comprising a thin strip of metal 20 and an integrally formed side wall 17, which serves to contain and align several components. Between the under side of one end of the terminal and adjacent the insulator strip is attached a spring 21. Spring 21, insulator strip 18, lateral extension 12 and terminal 20 are all gathered together and held by means of a rivet 22. As stated, tongue 14 is adapted to carry a contact 23 thereupon to mate with a contact 25 staked to spring 21, which is adapted to fit within the confines of a movable arm 27. One end 28 of movable arm 27 is staked to spring 21 at its contact carrying end and has contact 25 connected to the underside thereof. The other end 30 of movable arm 27 meets strip insulator 18 at a point directly above fulcrum bar 13 to form a pivot about which the movable arm 27, in cooperation with spring 21, is adapted to be angularly moved upon activation of strip 18 by the usual cam member included in an ignition timer system.

Referring to Fig. 3, there is shown the unique and novel construction of movable arm 27 as adapted to ride about the fulcrum 13 on insulator strip 18, and as further adapted to contain spring 21 thereupon and within side walls or lips 47 and 48 under proper stress and alignment. Movable arm 27 comprises a specially configured metallic form having a plurality of sections. It includes a first end section 30 and an end section 28 interconnected by a situated mid-section 42 having a general U-shaped configuration integrally joined to said sections, while hanging therefrom to place the convexity formed by the U-shaped section at a position lower than the other sections. The mid-section thus formed is adapted to be seated above the cam of the ignition breaker on the top surface 60 of the insulator strip 18, to be displaced when the cam meets the under side 61 of the insulator strip. This insulator strip, although being of thin cross-section, is enabled to act as a rubbing block. This is so because the mid-section of movable arm 27 places strip 18 into the necessary follower relationship with the actuating cam.

In order to place movable arm 27 under proper tension so as to rotate end 30 about the fulcrum arm 13, arm 27 has its surface 45 bounded by side lips 47 and 48 so as to form a cradle for receiving lower steel spring 21 on surface 45 within the confines of lips 47 and 48. The bowed stress is supplied spring 21 by staking it at one end 77 by means of a clamping rivet 22 passing through eyelet 49 cut therein and by staking the other end 50 to arm 27 at its end 41 via contact rivet 51 passing through eyelet 52.

In the operation of the fulcrum type ignition contact breaker, as heretofore described, the rubbing block constitutes the thin insulation strip which underlies the movable arm at its bent-down, U-shaped portion. The insulator strip further, at one end thereof, serves to insulate the arm from the base at both the stack and the fulcrum point.

This description of the novel fulcrum type ignition

contact breaker is intended to be merely illustrative and not exhaustive of the scope of the invention, which is to be taken rather from the appended claims, together with the description in the specification.

5 We claim:

1. An ignition contact breaker comprising, in combination, an assembly having a side wall adapted for adjustable relation to a timing cam, a movable contact arm having a contact, said arm adapted to be motivated by said cam, a fixed contact adapted to cooperate with said contact on said arm, an extension formed as part of said assembly, a spring attached to said arm placing stress thereon, fastening means holding said arm in fixed relation to said extension, an insulating strip held between said spring and said extension, said insulating strip resting on a fulcrum and extending substantially tangent to said cam to rest between said cam and said arm to insulate said arm from said cam while also forming a wear-resisting surface for bearing against said cam so as to move said arm on rotation of said cam.

2. An ignition contact breaker comprising, in combination, an assembly having a side wall adapted for adjustable relation to a timing cam, a movable contact arm having a contact, said arm adapted to be motivated by said cam, a fixed contact adapted to cooperate with said contact on said arm, an extension formed as part of said assembly, a spring lying against said arm placing stress thereon, fastening means holding said arm in fixed relation to said extension, an insulating strip resting on a fulcrum and held between said spring and said extension extending laterally therefrom, said insulating strip being substantially tangent to said cam to rest between said cam and said arm to insulate said arm from said cam while also forming a wear-resisting surface for bearing against said cam so as to move said arm on rotation of said cam.

3. An ignition contact breaker comprising, in combination, a mounting plate having a side wall, said side wall having means for adjustably moving said plate in relation to a cam operating with respect to said breaker, a movable contact arm having a contact at an end thereof, stack means connecting an end of said arm to said plate, means extending from said side wall carrying a fixed contact thereon, said latter contact being placed opposite said contact on said movable arm and adapted to mate therewith, a spring held in said stack and connected to said movable arm for placing stress thereon, a second extension connected to said plate, a fulcrum bar also extending therefrom, an insulating strip held between said spring and said second extension, said insulating strip extending substantially tangent to said cam to rest on said fulcrum bar between said cam and said arm, said strip insulating said arm from said cam while also forming a wear-resisting surface for bearing against said cam, said cam adapted on rotation to move said arm on said fulcrum bar for making and breaking electrical contact between said contacts of said breaker.

4. A fulcrum type ignition contact breaker comprising, in combination, assembly means adapted to be connected to the timer of an internal combustion engine, said assembly means comprising an extension and a side wall, said extension bent from said side wall at substantially a right angle thereto, a plurality of apertures cut through said side wall for adjustably adapting said assembly to said distributor, a stack connected to said assembly side wall including a terminal, a spring with one end held by said stack having a contact at a free end thereof, a fixed contact cooperating therewith, an insulator slab for said stack, an insulator strip acting as a rubbing block, fastening means holding all the components in the stack together, a moving arm placed beneath said steel spring, a tip end of said arm resting against said insulator strip, and a fulcrum connected to said side wall placed on the opposite side of said insulator strip beneath said tip end.

of said movable arm, the moving arm thus being movable about said fulcrum upon the lift of said insulator strip.

5. A fulcrum type ignition contact breaker comprising, in combination, assembly means adapted to be connected to the timer of an internal combustion engine, said assembly means comprising an extension and a side wall, said extension bent from said side wall at substantially a right angle thereto, a plurality of apertures cut through said side wall for adjustably adapting said assembly to said distributor, a stack connected to said assembly side wall including a metal terminal having a bent side piece, a stressed spring with an end held in stack and having a rivet passing through its free end to hold an upper contact, a lower contact cooperating therewith, an insulator block for said stack, an insulator strip on said block acting as a rubbing block, a rivet staking all the components in the stack together, a moving arm placed beneath said steel spring, a tip end of said arm resting against said insulator strip, and a fulcrum connected to said side wall placed on the opposite side of said insulator strip beneath said tip end of said movable arm, the moving arm thus being movable about said fulcrum upon the lift of said insulator strip.

6. A fulcrum type ignition contact breaker comprising, in combination, assembly means adapted to be connected to the timer of an internal combustion engine, said assembly means comprising an extension and a side wall, said extension bent from said side wall at substantially a right angle thereto, a plurality of apertures cut through said side wall for adjustably adapting said assembly to said distributor, a stack connected to said assembly side wall including a metal terminal, a bowed spring having an end attached thereto, said spring having a contact attached to a free end by means of a rivet, a fixed contact cooperating therewith, an insulator block for said stack, an insulator strip on said extension extending longitudinally acting as a rubbing block, fastening means holding the components in said stack together, a moving contact carrying arm placed beneath said bowed spring, said arm having a curved portion therein with a tip end of said arm resting against said insulator strip, and a fulcrum connected to said side wall placed on the opposite side of said insulator strip beneath said tip end of said movable arm, the moving arm thus being movable about said fulcrum upon the lift of said insulator strip.

7. A fulcrum type ignition contact breaker comprising, in combination, assembly means adapted to be connected to the timer of an internal combustion engine, said assembly means comprising an extension and a side wall, said extension bent from said side wall at substantially a right angle thereto, a plurality of apertures cut through said side wall for adjustably adapting said assembly to said distributor, a stack connected to said assembly side wall including a metal terminal, a bowed spring having an end connected to said stack, a contact rivet passing through a free end thereof, a fixed contact cooperating therewith connected to a tongue extending from said side wall, an insulator block in said stack, an insulator strip also included in said stack acting as a rubbing block, said strip extending toward said fixed contact, a bolt staking the components of said stack together, a moving arm having a U-shaped dependency placed beneath said bowed spring, a tip end of said arm resting against said

insulator strip, and a fulcrum connected to said side wall placed on the opposite side of said insulator strip beneath said tip end of said movable arm, the moving arm thus being movable about said fulcrum upon the lift of said insulator strip.

8. A fulcrum type ignition contact breaker comprising, in combination, assembly means adapted to be connected to the timer of an internal combustion engine, said assembly means comprising a bent lateral extension and an assembly side wall, said extension integrally joined to said side wall at substantially right angles thereto, a plurality of apertures cut through said side wall for adjustably adapting said assembly wall to said distributor, a stack connected to said assembly side wall including a terminal, a stressed spring connected to said stack at one end and having a rivet passing through its free end, a fixed contact cooperating therewith, a rectangular insulator block for said stack, a thin insulator strip acting as a rubbing block, a bolt staking all the components to said stack together, a moving arm having a sinuated portion placed beneath said steel spring, said arm having side lips for containing said stressed steel spring, a tip end of said arm resting against said insulator strip, and a fulcrum connected to said side wall placed on the opposite side of said insulator strip beneath said tip end of said movable arm, the moving arm thus being movable about said fulcrum upon the lift of said insulator strip by a moving cam.

9. A fulcrum type ignition contact breaker comprising, in combination, assembly means adapted to be connected to the timer of an internal combustion engine, said assembly means comprising a bent lateral extension and an assembly side wall having a top and a bottom side, said extension integrally joined to said side wall at substantially right angles thereto, a plurality of apertures cut through said side wall for adjustably adapting said assembly wall to said distributor, a mounting stack connected to said assembly side wall including a metal terminal, a stressed spring connected to said stack at one end and having a rivet for carrying a contact penetrating therethrough at a free end, a rectangular insulator block for said stack, a thin insulator strip on said block acting as a rubbing block, a bolt staking all the latter together, a fixed contact cooperating with said riveted contact, a U-shaped contact carrying movable arm placed beneath said steel spring, said arm having a sinuated portion and side lips for containing said steel spring, a tip end of said movable arm resting against said thin insulator strip, and a fulcrum arm connected to the bottom side of said assembly wall placed on the opposite side of said insulator strip beneath said tip end of said movable arm, the moving arm thus being movable about said fulcrum upon the lift of said insulator strip.
